Application October 10, 1935, Serial No. 44,386

10 Claims. (Cl. 60—52)

This invention relates to hydraulic presses and more particularly to a hydraulic device adaptable for use as a press or in connection with similar tools wherein a maximum number of applications of energy to a concentrated work point is desired, and especially where it is desirable that the application of a predetermined maximum amount of energy should be applied substantially instantaneously.

10 It is common practice, in connection with hydraulic pumps, to use a power source, such as an electric motor, of a power rating sufficiently high to store and maintain a constant pressure from which energy may be drawn at any time 15 and transferred to the point of application. Such pumps consume a very great amount of energy in maintaining the pressure and require large and expensive motors and complicated mechanisms in which a great amount of energy 20 is lost in the transfer from the point of generation to the point of useful work. Maintaining a high pressure at some point within such pumps necessitates the dissipation of a great amount of energy other than that required to do 25 the work.

It is an object of the present invention to provide a hydraulic press using a power source of minimum size and power rating and in which the energy is directed from a suitable energy 30 conserving device, preferably a flywheel, directly to the point of application, and in which all of the energy used is expended in useful work at the moment of application.

The present invention maintains a source of 35 maximum potential energy and transfers a desired amount of this potential energy to the point of application without appreciable loss of energy during its transmission. In other words, the invention uses a minimum amount of power 40 to maintain a potential energy at a maximum and this maximum amount of energy is available for useful work at a desired point of application with a minimum loss of energy during the transfer from the source to the point of application.

45 A further object is to provide a hydraulic device of the character described having a completely closed hydraulic circulating system, so far as the flow of fluid is concerned, in which there is substantially no loss of fluid and all the parts are self-lubricating by means of the fluid used within the pumping system.

Another object is to provide a novel reversing 50 arrangement which is entirely automatic and controlled solely by fluid pressure at the time

of application of such pressure to the work; that is, the reverse operation is preferably accomplished by the predetermined maximum useful pressure applied to the work.

A further object is to provide a hydraulic press 5 of minimum size and maximum energy producing capacity which will be of few parts, without gears, or mechanically operated trips, valves, or detents, and in which all separate pipes or conduits are eliminated; also, which may be manufactured at a minimum cost and be easily and quickly assembled.

The invention also contemplates a momentum controlled fluid pressure unit of very small size relative to the pressure developed and which may 15 be easily and cheaply installed in connection with existing presses without materially increasing the overall dimensions of the original installation. In fact, in many instances the dimensions 20 may be materially reduced. Also the installation of the unit may be accomplished very quickly and at a minimum cost.

Further objects will be apparent from the specification and the appended claims.

In the drawings:

Figure 1 is a perspective view of one embodiment of the invention incorporated in a portable device having a piston operated pressing tool associated therewith.

Fig. 2 is a somewhat diagrammatic view illustrating the use of a plurality of pistons with a single controlling valve.

Fig. 3 is a vertical section through the pressure developing unit and taken on a line substantially corresponding to line 3—3 of Fig. 4.

Fig. 4 is a left hand end view of the embodiment illustrated in Fig. 3.

Fig. 5 is a transverse sectional view through the lower base of the machine and the control valve therein and taken on a line substantially 40 corresponding to line 5—5 of Fig. 3.

Fig. 6 is a longitudinal sectional view through a controlling valve somewhat similar to that illustrated in Fig. 5, but arranged to provide for automatic fluid-controlled return stroke of the 45 work piston. The conduits or channels in this embodiment are illustrated diagrammatically.

Fig. 7 is a somewhat diagrammatic side elevation illustrating one application of the pressure unit to an ordinary press.

Fig. 8 is a front view of the embodiment illustrated in Fig. 7.

Fig. 9 is a vertical section through the reciprocating pump valve and the channels or conduits leading to the reservoir and is taken on a line 55

substantially corresponding to line 9—9 of Fig. 3.

Fig. 10 is a diagrammatic view illustrating the position of the controlling valve and associated elements after the valve has been manually or otherwise moved to fluid blocking position to cause a working operation of the device.

Fig. 11 is a diagrammatic view similar to Fig. 10 but with the controlling valve moved by bypassed fluid pressure to pressure relieving position, and with the associated elements moved to a position whereby energy is stored to continue the movement of the valve to the normal position shown in Fig. 5 after pressure to the by-pass is closed.

Fig. 12 is a transverse sectional view through the controlling valve and illustrates the return conduit to the reservoir and is taken on a line substantially corresponding to line 12—12 of Fig. 5.

Fig. 13 is a detail section taken on a line substantially corresponding to line 13—13 of Fig. 5.

Fig. 14 is a fragmentary elevation of an indicating dial arrangement for determining the operating pressure.

Referring to the drawings in detail, the embodiment illustrated comprises a pump unit 1 which encloses substantially all of the operating parts and which, due to the small number of parts used, may be of a minimum size to provide a maximum amount of available energy. The unit 1 comprises an integral lower base 2 for supporting the pistons, and an upper base 3 having inturned flanges 4 by which it may be secured to the base 2 by means of suitable bolts 5 or machine screws 5. The upper base 3 provides a reservoir 6 for containing a supply of a suitable fluid, such as oil, and is provided with a cover 7 having vent openings 8 therein and a baffle plate 9 arranged to prevent the fluid from being thrown through the vents. It will be apparent that the lower and upper bases 2 and 3 may be a single integral casting if desired.

A crank shaft 10 is mounted in suitable anti-friction bearings 11 in the upper base 3, and a flywheel or so-called "balance wheel" 12 of appropriate size, in accordance with the energy to be developed by the machine, is secured to the crank shaft 10 outside the casing as illustrated. A comparatively small electric motor or other power source 13 is preferably directly connected to the crank shaft 10 as illustrated in Fig. 1. It will of course be apparent that any suitable transmission, such as a belt, may be used from the motor 13 to the crank shaft 10 in accordance with the speed required of the pump.

A plurality of pistons 14 and 15 are mounted in suitable sleeves 16 and 17, respectively, which sleeves are inserted in the lower base 2 to provide suitable cylinders for the pistons. The piston 14 is somewhat shorter than the piston 15 and is operatively connected to an eccentric 18 on the crank shaft 10 by means of a connecting rod 19. In a similar manner the piston 15 is connected to an eccentric 20 on the crank shaft 10 by means of a connecting rod 21. The eccentrics 18 and 20 are 180 degrees offset on the crank shaft as illustrated in Fig. 4, whereby when one piston is being raised, the other piston is moving downwardly.

A valve sleeve 22 is inserted in the base 2 between the pistons 14 and 15 and preferably in the same vertical plane and is provided with a reciprocating valve 23 operatively connected to an eccentric 24 on the crank shaft 10 by means of a connecting rod 25. The valve eccentric 24

is preferably positioned at ninety degrees relative to the piston eccentrics 18 and 20 as illustrated in Fig. 4. It will therefore be apparent that when the pistons are at the extreme limits of their stroke and their eccentrics are positioned as in Fig. 4, and moving in the direction of the arrow, the valve 23 will be in its mid-stroke position and traveling at its highest speed, and, vice versa, when the pistons are in mid-stroke and traveling at their highest speed, the valve 23 will be at or adjacent its stroke limit and traveling at its slowest speed. This relationship is important for the proper co-operation of the valve and pistons in order to prevent pressures developing in the system which might cause a dissipation of energy which could otherwise be made available for useful work.

The valve 23 is provided with reduced portions forming passages 26 and 27 between the valve and the sleeve 22. The valve is also provided with spaced comparatively wide split rings 28 and 29. These rings are hardened and ground step-split rings, the step split preventing leakage of oil from either side to the other. The sleeve 22 is reduced in diameter at its upper end to provide a channel 30 communicating with the oil chamber 6 and the piston passage 26 through a series of perforations 31 in the sleeve wall. The lower end of the cylinder 16 of the piston 14 communicates with the interior of the valve sleeve 22 by means of a channel 32 in the base 2 and a series of openings 33 through the sleeve 22. The lower end of the cylinder 17 of the piston 15 communicates with the interior of the sleeve 22 by means of a channel 34 and a series of openings 35 through the sleeve. It will therefore be obvious that if oil is supplied to the cylinders of the pistons 14 and 15, the pistons will alternately pump this oil into the interior of the sleeve 22 if the valve 23 is positioned to permit the oil to pass through the respective openings in the sleeve.

Another series of perforations 36 is provided in the sleeve 22 and positioned intermediate the openings 33 and 35. These openings 36 communicate with a so-called "work pressure passage" 37 in the base to which may be connected a suitable cylinder 38 having a work applying piston 39 therein normally held in the position illustrated by means of a light spring 40. This spring is only sufficiently strong to return the piston to normal position after it has been applied to the work.

The operation of the above described portion of the device is as follows:

The piston 14 has just completed its downward stroke (Fig. 3) and during this downward stroke, the valve 23 has been making the upper half of its upward stroke and the upper half of its downward stroke. Therefore the valve ring 28 has been above the openings 33 at all times during the downward stroke of the piston 14, and the valve ring 29 has necessarily been moved upwardly and downwardly in a corresponding manner from and to the position shown in Fig. 3 and relative to the openings 35. It is therefore apparent that during the downward stroke of the piston 14, the fluid will be forced from the cylinder of the piston 14 through the conduit 32, the series of openings 33, the valve passage 27, and through the series of openings 36 into the work pressure channel 37.

During the time that the piston 14 is substantially stopped in its lowermost position, the valve 23 is traveling downwardly at its highest rate of

speed. The ring 28 therefore quickly passes the openings 33 leading to the piston, at a time when the piston is not moved sufficiently to cause any material pressure or vacuum in the channel 32 and thereby dissipate energy. As soon as the valve 23 has moved downwardly sufficiently to permit the ring 28 to pass the openings 33, the piston 14 increases its upward speed due to the relative position of the eccentric on the crank shaft, and oil is then drawn from the reservoir 6 through the sleeve channels 30, the openings 31, the valve passage 26, the openings 33 and the channel 32 leading to the cylinder of the piston. The work-pressure channel 37 into which the oil is pumped by the downward movement of the piston 14 is normally open to the reservoir 6 through a suitable channel and therefore there will be no appreciable pressure developed in the system due to the fact that the oil freely circulates from the reservoir 6 through the cylinder of the piston 14 and into the channel 37 from which it freely returns to the reservoir 6. Means is provided whereby the passage from the work pressure channel 37 to the reservoir 25 may be temporarily closed when desired to apply energy for the operation of the work piston. This mechanism will be described in detail later.

The piston 15 and the fluid controlled thereby operates in exactly the same manner; that is, during the upward stroke of the piston 15, the valve ring 29 is positioned above the series of openings 35 in the valve sleeve 22 and the piston therefore draws fluid from the reservoir 6 through a conduit 41 which communicates with the open bottom end of the valve sleeve 22, and, through the series of openings 35, also communicates with a channel 34 leading to the lower end of the cylinder of the piston 15. While the piston 15 is at the upward limit of its stroke, the valve 23 moves downwardly to position the ring 29 below the openings 35. Therefore, during the downward stroke of the piston 15, the fluid in the conduit 34 flows through the openings 35, the valve passage 27, and through the sleeve openings 36 into the work-pressure passage 37 and from there returns to the reservoir 6 through the return passage previously mentioned. It will therefore be apparent that, when the return passage from the channel 37 to the reservoir 6 is closed, all down strokes of the pistons will create a pressure in the work passage 37 and against the working piston 39 to move the piston against the work. As soon as this pressure is released by opening the return passage, a light spring 40 will return the piston to the normal position illustrated.

In order to permit free flow of fluid from and to the reservoir 6 and to provide free and unrestricted movement of the valve 23 the valve is provided with an internal bore as indicated by the dotted lines 41a in Fig. 3 and in full lines in Fig. 9. The open lower end of this bore communicates with the reservoir 6 through the channel 41 and the upper end communicates with the reservoir through openings 41b in the valve and openings 31 and passage 30 in the valve sleeve. This arrangement permits the valve to move freely and without material resistance and permits free flow of fluid to and from the cylinders thereby providing a so-called balanced valve.

In order to close the return passage from the channel 37 to the reservoir 6 and apply pressure to the piston 39 and to reopen the passage as soon as the work has been accomplished, a control mechanism is provided which is illustrated

in detail in Fig. 5. This control mechanism comprises a horizontally positioned valve member 42 which is slidably mounted in a sleeve 43 inserted in the base as illustrated. This valve is provided with a restricted portion 44 providing a fluid passage 45 within the sleeve. The valve is also provided with a special wide step-split ring 46 and step-split piston rings 47. The work-pressure channel 37 communicates with the valve passage 45 through a series of openings 48 in the valve sleeve 43, and the valve passage 45 communicates through a similar series of openings 49 in the valve sleeve, with a vertical conduit 50 indicated by the dotted circle in Fig. 5 and leading directly to the reservoir 6. It will therefore be clear that with the valve 42 in the position illustrated in Fig. 5 any fluid pumped into the passage 37 will freely pass through the sleeve openings 48, the valve passage 45, the sleeve openings 49 and through the conduit 50 into the reservoir from which it is returned to the pistons in the manner previously described. Therefore, with the valve in this normal position as illustrated, there will be a free circulation of fluid and no material pressure will be developed. It will also be apparent that if the valve 42 is moved to the right as shown in Fig. 10 so that the ring 46 passes the openings 48, the passage to the reservoir will be closed and pressure will immediately develop in the channel 37 to operate the piston 39, and as soon as the valve is moved to the left again to uncover the openings 48, a further unrestricted circulation of the fluid will again take place and the piston 39 will be returned to its normal position by the spring 40.

The valve 42 is provided with a longitudinal bore 51 therethrough, the bore being enlarged adjacent the right hand end to provide a valve seat 53. The right hand end of the valve bore 51 is closed by means of a plug 54 threaded 40 therein and provided with openings 55 for the circulation of fluid therethrough. A so-called "poppet valve" 56 is seated against the valve seat 53 by means of a spring 57 bearing against the plug 54. The poppet valve 56 is provided 45 with a valve stem 58 extending through the control valve and extending from the base and provided with a suitable packing box 59 through which the valve stem may be moved. A piston 60 is positioned adjacent the right hand end of 50 the valve sleeve 43 and normally held against the end of the valve sleeve 43 by means of a spring 61 bearing against a suitable plug or cap 62 having an inwardly extending portion 62e for the purpose of limiting the outward stroke of the 55 piston.

The piston 60 is provided with a restricted portion 63 forming a passage communicating with the bore of the valve sleeve 43 through auxiliary passages 43a. A channel 64 communicates with 60 the bore of the valve sleeve through the passage formed by the restricted portion 63 of the piston 60 and the passages 43a. This channel 64 also communicates with the pressure conduit 37 through normally closed passages 65 and 66. 65 These passages 65 and 66 are normally closed by means of needle valves 67 and 68, respectively. The valves 67 and 68 are yieldably retained in closed position by means of springs 69 and 70. The tension of the spring 69 controlling the 70 valve 67 may be manually adjusted by means of a thumb screw 71 bearing against the spring 69. The tension of the spring 70 controlling the valve 68 may be adjusted by means of the screw 70a bearing against the spring and secured by means 8

of a lock nut 72. The valve 67 may be adjusted to open at the maximum working pressure in the pressure in the passage 37, and the valve 68 is adjusted to function at a somewhat higher pressure and provide a safety valve in case the valve 67 should stick or fail to operate properly.

The operation of the device is substantially as follows:

With the machine running at comparatively high speed and the parts in the position described, the fluid will be freely circulating from the reservoir through the conduits and back to the reservoir. However, if the valve stem 58 is pushed inwardly either manually or otherwise, the poppet valve 56 will open slightly against the pressure of the spring 57, thereby permitting the fluid in the right hand end of the sleeve and adjacent the piston 60 to pass freely through the openings 55 in plug 54 and through the valve bore 51 to the opposite end of the valve, thereby permitting the valve to move freely to the right to close the sleeve openings 48. An opening 73 through the restricted portion of the valve wall permits the fluid to flow freely from or to the interior of the valve. This arrangement permits the valve to be freely moved to the right by any suitable means such as a solenoid 74 or a manually or mechanically operated lever.

As the valve moves to the right, the series of valve sleeve openings 48 communicating with the pressure channel 37 will be closed by the split ring 46 and as soon as this takes place, pressure develops in the passage 37 to move the working piston 39 to apply pressure to the work. As soon as the pressure is increased to a predetermined value, to which the needle valve 67 is adjusted, the valve 67 will open and some pressure will be applied through the passage 64 between the valve piston 60 and the valve 42. The high pressure also tends to expand the wide split ring 46, as well as the other piston rings 47, and these rings therefore develop considerable friction against the walls of the sleeve 43 to prevent movement of the valve. These rings are comparatively wide and are normally of larger dimension than the piston chamber. Therefore their natural tendency to expand forces them snugly against the walls of the valve chamber so that there is substantially no fluid pressure against the outside of the rings. However, the grooves in the piston are preferably somewhat deeper than the thickness of the rings so that the pressure of the fluid in the grooves and against the inside of the rings presses them snugly against the walls of the valve chamber. The spring 61 controlling the piston 60 is therefore arranged to provide less resistance than the friction of the valve 42, and the fluid back of the piston is freely vented to the chamber by a suitable conduit indicated by the dotted circle 61' in Fig. 5 and in full lines in Fig. 13. The pressure against the piston 60 will therefore first compress the spring 61 and the piston will move to the right against the stop 62e. As soon as the piston strikes the stop 62, the pressure of the fluid from the passage 64 will overcome the resistance of the split rings of the valve and the valve will move to the left until the sleeve openings 48 leading from the passage 37 are open slightly. At this point the valve 42 would stop and would not completely uncover the openings 48 as the pressure of the fluid is immediately relieved. However, as soon as this pressure is relieved, the piston 60 is returned to its normal position by means of the spring 61 thereby mov-

ing the piston 60 to the left. The pressure of the piston on the fluid intervening between the piston and the valve forces the valve completely to the left to the normal position illustrated and thereby quickly and completely opens the sleeve passages 48, thereby preventing any restriction in the free flow of the fluid through the entire system. This entire operation is substantially instantaneous and the valve does not hesitate at an intermediate position.

In order to provide for remote control of the device and instantaneous application of pressure at any desired moment, a solenoid 74 or any other suitable electrical device may be provided to operate the valve stem 58, whereby the valve may be moved inwardly to close the return passage to the reservoir. This arrangement is illustrated in Fig. 1 in which the solenoid may be mounted in a suitable casing 75 and connected to a suitable controlling device such as a trigger 20 or lever 76 which may be arranged to control an electrical switch or other suitable mechanism. In Fig. 1 the trigger 76 is mounted on a pressure applying tool 77 in which a punch 78 is connected to the piston 39 mounted in the cylinder 38, the cylinder 38, being connected to the pressure passage 37 by means of a conduit 79.

A number of pistons may be mounted in line on a single crank shaft as illustrated in Fig. 3, the crank shaft being suitably extended for the purpose, or, the pistons and reciprocating valves may be arranged in a ninety degree V-shaped assembly, such as illustrated diagrammatically in Fig. 2 and the control valve may be placed in the angle as shown.

Regardless of the number of pistons or the number of reciprocating valves associated therewith, the application of pressure may be effectively controlled by means of a single control valve, such as illustrated in Fig. 5.

It is sometimes desirable to return the power-applying piston 39 by fluid pressure instead of by means of the spring 40. In such cases, the work piston performs a complete cycle by fluid pressure, that is, a working movement and return with each control movement of the valve 42. In order to accomplish this, the control valve is slightly modified as illustrated in Fig. 6.

The embodiment illustrated in Fig. 6 comprises a valve sleeve 80 having a valve 81 slidably mounted therein. The valve 81 is somewhat similar to the valve 42 illustrated in Fig. 5 and is provided with a special type of wide split rings 82 and 83, as well as an ordinary split ring 84 adjacent the end of the valve. The valve is provided with two restricted portions forming passages 85 and 86, respectively. The internal construction of the valve is substantially identical with the valve 42 and is provided with an internal longitudinal bore 51a, a valve seat 53a, a poppet valve 56a normally seated by means of a spring 57a and retained by means of a perforated plug 58a having openings 55a therethrough. The valve 56a is provided with a valve stem 58a which may be controlled manually or by a suitable solenoid as previously described. A piston 60a corresponding to the previously described piston 60 is also provided and normally retained against the sleeve 80 by means of a spring 61a.

A small auxiliary valve 87 is slidably mounted in the left hand end of the valve sleeve 80 and is provided with a passage 88 therethrough to permit the free flow of oil from one end of the valve to the other, and is also provided with a special wide step-split piston ring 89. The valve stem

- 58a extends through this supplementary valve and the valve may be pushed inwardly with the main control valve 81 to the position illustrated, by means of a collar 90 secured to the valve stem. 5 The main control valve 81 is shown in this embodiment at the extreme right hand end of the sleeve and when it returns to the extreme left hand limit of its movement, the reduced end 91 engages the auxiliary valve 87 and moves it to the 10 extreme left end of the valve sleeve 80 and thereby uncovers suitable sleeve openings associated with the auxiliary valve.

In this construction the cylinder of the work piston 39a is not directly connected to the pressure passage 37 leading from the main reciprocating valve, but, instead, one end of the cylinder communicates with the valve passage 85 by means of a conduit 92 leading to a series of 15 openings 93 in the valve sleeve. The other end 20 of the cylinder 38a is connected to the interior of the sleeve 80 by means of a conduit 94 communicating with the interior of the sleeve through a series of openings 95. The pressure 25 passage 37 is provided with a conduit 96 communicating with the interior of the sleeve through a series of openings 97 at the left hand end of the sleeve. The pressure passage 37 also 30 communicates with the interior of the sleeve adjacent its center by means of a conduit 98 communicating with the interior of the sleeve through a series of openings 99. Another series 35 of openings 100 is provided through the sleeve 80 and a passage 101 communicates with the space at the left hand side of the auxiliary valve 81 so as to permit free flow of oil from the back 40 of the auxiliary valve to the reservoir 6 through a conduit 100a, when the valve is moved. Another series of openings 102 are provided adjacent the other end of the sleeve 80 and communicating 45 with the valve passage 86 and a conduit 86a leading to the reservoir 6 to permit free flow of oil to and from the valve.

The operation of the device is substantially as follows:

- 45 With the valve 81 in the position illustrated, the mechanism is in position to provide a forward stroke of the work piston 39a and the pressure will immediately be applied from the pressure passage 37 through the conduit 98, sleeve openings 99, valve passage 85, sleeve openings 93, and through the conduit 92 to the right hand end 50 of the work cylinder 38a to move the piston 39a against the work. During this movement of the piston 38a the oil from the left hand end of the 55 work cylinder freely moves through the conduit 94 and sleeve openings 95 and back to the reservoir through the return conduit 100a. As soon as the work is contacted and the pressure increases to a predetermined amount controlled 60 by the adjustable valve 67, this valve 67 raises slightly and permits pressure to be applied through the conduit 64a to the right hand end of the valve 81. The friction of the valve 81 due 65 to the pressure on the rings prevents its being moved and the piston 60a moves to the right compressing the spring 61a until it contacts the stop 62a. As soon as the piston strikes the stop 62a the pressure from passage 64a overcomes the resistance of the split rings of the valve 81 70 and the valve moves to the left until the rings 82 and 83 partially pass their respective sleeve openings 95 and 93. At this point the valve 42a would stop and would not completely uncover the sleeve openings for reverse flow of fluid as 75 the pressure is temporarily relieved. However,

the instant this pressure is relieved the piston 60a is moved by the pressure of the spring 61a against the piston and the fluid intervening between the piston and valve 81, thereby moving the valve still further to completely uncover the sleeve openings, and reverse the application of pressure to the work piston 39a. This operation is, of course, substantially instantaneous and the pressure is not increased above the predetermined work pressure.

With the valve in this latter position, the pressure is applied from the pressure passage 37 through conduit 98, the sleeve openings 99, valve passage 85, sleeve openings 95 and the conduit 94 to the left hand end of the work cylinder 38a, thereby returning the piston 39a to its normal position. During this movement of the piston 39a the oil in the right hand end of the cylinder 38a freely moves through the conduit 92, sleeve openings 93, valve passage 86, and returns to 20 the reservoir 6 through the return conduit 86a. As soon as the piston 39a returns to its normal position illustrated, the pressure in the pressure passage 37 again opens the valve 67, admitting pressure to the channel 64a and to the right 25 hand end of the control valve 81. This pressure first moves the piston 60a against the stop 62a again compressing the spring 61a and then moves the valve 81 to the left. During this latter movement, the outwardly extending end 91 30 of the control valve pushes the auxiliary valve 87 also to the left until the ports 97 are partially opened, thereby again relieving the pressure. The compressed spring 61a acting on the piston 35 and valve then moves the valve 81 and auxiliary valve 87 still farther to the left to completely open the ports 97. The fluid then flows freely through the ports 97 and the return conduit 100a 40 to the reservoir 6. In this latter position, it will be apparent that the pumping pistons may continue to operate with the result that there will be no energy absorbing pressure generated except such as required for the free circulation of 45 oil through the conduits.

In returning the work piston 39a to its normal position after a work stroke it is not necessary to use as high a pressure as in the work stroke, and adjustable means is provided whereby the pressure may be limited as found desirable in 50 accordance with the weight and friction of the piston. An auxiliary duct 94a connects the channel 94 with the duct 64a, and this auxiliary duct is normally closed by an adjustable yielding needle valve 94b. This valve may be similar to 55 valve 67; however, it may be adjusted to open at a much lower pressure, thereby operating the valve 81 to relieve all pressure as soon as the work piston completes its cycle.

The compression of spring 61a controlling the 60 valve-moving piston 60a may be adjusted by means of a screw 61b and lock nut 61c. A similar adjusting means is of course applicable to the embodiment illustrated in Fig. 5.

It should be particularly noted that in the 65 embodiments illustrated, there are no separate pipes or conduits and no couplings or other similar devices. All of the fluid conduits or channels, as well as the valve and piston cylinders, may be provided merely by boring, drilling, or 70 otherwise machining suitable passages in a single block of material.

It is believed that the present invention provides a device capable of developing a higher working pressure with a smaller machine and

smaller power source rating than heretofore known to the art, for instance, Figs. 3 and 4 of the present drawings are one-half size and Fig. 5 is full size of machines now in actual use, and these machines are capable of developing more than 5,000 pounds working pressure at 1200 R. P. M. with a $\frac{1}{4}$ H. P. motor and operating a work-applying piston 150 or more times per minute.

10 The advantages of the device will be readily appreciated when it is understood that the size of the casing of the unit developing the above noted power is only 6" x 7" x 12".

15 An important feature of the present invention is that no pressure is generated higher than the pressure applied to the work and no appreciable pressure is ever generated except at the time of application to the work. The control valve may operate at a pressure considerably lower than the work pressure. A dial or other indicating device such as illustrated in Fig. 14 may be provided for the adjustable valve 67. The thumb screw 71 may be arranged to rotate a pivotally mounted dial $\frac{1}{4}$ b via means of a pinion $\frac{1}{4}$ b secured to the thumb screw shaft and meshing with a gear $\frac{1}{4}$ c on the dial.

20 The small size and low cost of the device relative to the energy developed make it particularly desirable for use in connection with presses already installed, as it may be located adjacent thereto or supported within or on the frame, as shown in Figs. 7 and 8, and saves the cost of installation of a new machine.

25 In Figs. 7 and 8 the unit 1 may be mounted on any suitable part of an ordinary press frame 102; for instance, it may be supported on a shelf 103 or it may be supported entirely within the frame. The motor 13 may also be mounted in any suitable manner within the frame of the press and may drive the flywheel 12 by means of a belt 104 on suitable pulleys. The unit is operatively connected to a pressure cylinder 105 by means of the conduits 92 and 94, and when a spring is used to return the work piston the conduit 94 may be omitted.

30 The controlling valve of the pressure unit may be manually operated, or any suitable switching arrangement may be used for momentarily connecting the solenoid circuit to a suitable electrical power source.

35 Modifications may be made by those skilled in the art without departing from the spirit of the invention, and it is therefore desired that the invention be limited only by the scope of the appended claims.

Having thus described this invention, what is claimed and desired to be secured by Letters Patent is:

40 1. In a momentum operated pressure generating unit for a hydraulic press, said unit having conduits for free circulation of fluid therethrough, the combination with a pump for freely circulating said fluid, of an independently operable valve for blocking said fluid to enable said momentum to generate a predetermined high pressure in said fluid, an energy storing means associated with said valve, and means automatically operable by said predetermined high pressure to direct less than said predetermined pressure to move said valve to reduce said high pressure and to store energy in said storing means, said storing means automatically operating to completely release said pressure.

45 2. A hydraulic press comprising conduits forming a fluid circuit, a body having a normally

5 constant momentum at a predetermined velocity, a power source for maintaining said velocity, means operable by said body to maintain fluid freely circulating in said circuit, movable means for obstructing said circuit to cause said momentum to create a high pressure in a part of said circuit, means for directing said pressure to a work surface, means for directing said pressure to store energy to move said obstructing means and substantially simultaneously directing said pressure to move said obstructing means to partially relieve said pressure, said storing means being adapted to continue the movement of said obstructing means to completely relieve said pressure.

10 3. In a press of the character described having a fluid pressure conduit and momentum-controlled means for maintaining a substantially constant flow of fluid therethrough, said conduit having unobstructed communication with a work-performing means, a movable member for closing said conduit to enable said momentum to create a high pressure therein, a fluid-filled by-pass communicating with said pressure conduit and with said member, means normally closing said by-pass to trap fluid therein to normally prevent movement of said member to close said pressure conduit, means operable to vent said by-pass and permit movement of said member to close said pressure conduit, said by-pass closing means being operable at a predetermined high pressure in said pressure conduit to admit pressure to said by-pass whereby said pressure will move said member to open said pressure conduit.

15 4. In a high pressure hydraulic power unit for pressure applying tools, said unit having fluid filled conduits for a free fluid cycle, the combination with power storing drive means for freely circulating said fluid through said conduits, of means for blocking one of said conduits to enable said power storing drive means to exert a substantially instantaneous high pressure in said blocked conduit, a normally closed fluid duct for directing pressure from said blocked conduit to said blocking means to cause said blocking means to reduce the pressure in said blocked conduit, means to open said duct at a predetermined pressure in said blocked conduit and to close said duct with a drop in pressure, resilient power-storing means operable by pressure in said duct, said resilient means normally operating after said duct is closed to direct stored power to cause said blocking means to completely relieve the pressure in said blocked conduit and enable free circulation of said fluid.

20 5. A hydraulic press comprising a fluid reservoir, fluid circulating conduits associated with said reservoir, a flywheel, a power source for driving said flywheel at a predetermined constant rate, means operatively connected to said flywheel to freely circulate fluid from and to said reservoir through said conduits, a reciprocable piston, a movable valve for simultaneously blocking said fluid circulation and directing a predetermined pressure therefrom to one side of said piston, means for directing pressure to move said valve to relieve the pressure from said one side of said piston and direct pressure to the other side, said last means being automatically operable to again direct pressure to move said valve to permit free fluid circulation and stop said piston after a single cycle.

25 6. In a comparatively small pressure generating unit having a momentum controlled circulat-

ing fluid circuit, a piston valve slidable to close said circuit to enable said momentum to develop a predetermined fluid pressure, and to direct said pressure to a first work conduit arranged to control a work performing means, an auxiliary valve movable simultaneously with said piston valve to obstruct a second work conduit arranged to control a work performing means, means operable at said predetermined pressure in said first work conduit to move said piston valve to release the pressure therein and simultaneously direct the pressure to said second work conduit, and means operable at a predetermined pressure in said second work conduit to move said piston valve to release the pressure in said second work conduit and simultaneously move said auxiliary valve to permit free circulation of said fluid circuit.

7. A press of the character described, comprising an unobstructed fluid circuit including a work pressure chamber for directing pressure to a work performing means, a pump for freely circulating fluid in said circuit, a fly wheel operably connected to said pump, power means constructed and arranged to supply only sufficient energy to said flywheel to maintain a predetermined constant momentum and only sufficient energy to said pump to freely circulate said fluid, movable means for obstructing said fluid circuit between said pressure chamber and the intake of said pump to enable said momentum to create a pressure in said working chamber greater than energy supplied from said power means during the work period, a fluid channel for directing said fluid pressure directly against said obstructing means to open said fluid circuit, and means for venting said channel to said circuit to enable free movement of said obstructing means to obstructing position.

40 8. In a momentum operated hydraulic press having conduits for free circulation of fluid therethrough, means operable to block said fluid to enable said momentum to generate a high pressure in said blocked fluid, means to enable said pressure to perform work, energy storing means, and means automatically operable at a maximum predetermined pressure to enable energy to be stored in said storing means, said blocking means being movable by fluid pressure to at least partially reduce said working pressure, and said storing means being automatically operable to completely release said pressure after said partial reduction.

9. A power unit of the character described, comprising an integral pump and channel block forming one wall of a fluid reservoir, said reservoir being at atmospheric pressure, channels in said block to enable fluid to be freely circulated from and to said reservoir, one of said channels being constructed and arranged to direct fluid pressure therein to a work performing means, a pump in said block and forming a part thereof to freely circulate fluid through said channels, a valve in said block and movable to interrupt the circulation of fluid in said channels to cause the fluid in one of said channels to exert a working pressure against said work performing means, a normally closed fluid filled by-pass channel in said block between said pressure conduit and said valve and arranged to normally cause the fluid therein to prevent movement of said valve, control means operable from outside said block to vent said by-pass and enable movement of said valve to obstructing position, and means operable at a predetermined working pressure to move said valve to allow circulation of said interrupted fluid.

10. A power unit of the character described, comprising an integral pump and channel block forming one wall of a fluid reservoir, said reservoir being at atmospheric pressure, channels in said block to enable fluid to be freely circulated from and to said reservoir, one of said channels being constructed and arranged to direct fluid pressure therein to a work performing means, a pump in said block and forming a part thereof to freely circulate fluid through said channels, a piston valve longitudinally movable to interrupt the circulation of fluid in said channels to cause the fluid in one of said channels to exert a working pressure against said work performing means, a normally closed fluid filled by-pass channel between said pressure channel and one end of said valve and arranged to cause fluid therein to normally prevent movement of said valve, said valve having a normally closed longitudinal bore, a vent valve in said bore, means accessible from outside said block to open said vent valve to vent said by-pass and simultaneously move said valve to obstruct said circulating fluid, and means operable at a predetermined working pressure to move said valve to allow circulation of said interrupted fluid.
